PUMP, COMPRESSOR, AND THE LIKE

James L. Kempthorne, Montclair, N. J.

Application February 24, 1932, Serial No. 594,789

8 Claims. (Cl. 103—142)

This invention relates to an improved pump or compressor. The pump or compressor is efficient by reason of the small number of parts and the compactness of the construction which latter characteristic makes the pump particularly adapted for small installations such as domestic refrigerators.

The invention is illustrated in the accompanying drawings in which Figure 1 is an elevation, partly in central section, of a pump embodying my invention. Figure 2 is an end view with the face-plate of the pump removed. Figure 3 is a detail section illustrating the rotor in elevation. Figure 4 is a central section of a modified form of pump. Figure 5 is an end view of the pump in Figure 4 with the face plate removed. Figure 6 is a longitudinal section of another modification. Figure 7 is a detail section on line 7 in Figure 6 but with the rotor removed. Figure 8 is a section on line 8—8 in Figure 6 and Figure 9 is a view similar to Figure 7 showing the abutment plate turned at a right angle to the showing in Figure 7.

The simplest form is shown in Figures 1, 2 and 3 and will be described first. The machine comprises the casing 10 made to conform to the place in which it is to be used. I show the casing as mounted on a foot or base 11 and supporting the bearing 12 of any desired construction. The shaft 13 rotates in the bearing 12 and extends into a hollow or chambered part of the casing. This chamber is substantially hemi-spherical in shape having the curved wall 14. Opposite the curved wall and acting as a closure for the chamber is a face plate 15 shown held in place by bolts 16. The inside face 17 of this plate is straight and smooth.

The rotor 18 is fitted inside the chamber of the casing and fits into the curved wall 14 but has on its outer surface two converging flat faces 19 and 20. I install a sealing strip 21 in a half round groove 22 in the rotor. The sealing strip has a flat face against the face 17 and a rounded face in the groove 22 to enable the strip to rotate with the rotor by rocking in the groove. This groove 22 extends across the rotor at the place where the planes of two faces 19 and 20 converge. The ends 21a of strip 21 are rounded on the same radius as that of the wall 14 and the rotor and its sealing strip form a unit that rotates in the chamber in the casing and while the rotor rotates it rocks.

To allow for this rocking and thus also to permit rotation of the rotor, the shaft and rotor have co-operating parts which in the form shown com-

prise a slot 23 in the curved or rear face of the rotor and a square end 24 on the shaft 13. This square end 24 fits into the slot 23 and insures the turning of one with the other. I have shown an inlet port at 25 and an outlet port at 26. The end 24 of the shaft need not be square but can be of any polygonal shape that will insure the desired connection to permit the rocking of the rotor and also cause the rotation of the rotor. Suitable packing rings 27 can be installed for insuring against leakage behind the sealing strip 21. It will be noted that the sealing strip 21 serves to open and close the ports 25 and 26 as it rotates with the rotor 18.

As the rotor is rotated in the chamber of the casing and against the flat surface 17, first one and then the other of the faces 19 and 20 is close up to the flat surface 17 and also alternate in occupying a position spaced from the flat surface 17 to form the fluid-receiving space 28. The axis 20 of the shaft 13 is at an angle to the plane of the surface 17 and bisects the surface 17 at the center of the surface.

Assuming the pump is in the position shown in Figure 1 with one face 19 of the rotor at the top and the other face 20 of the rotor at the bottom, the space 28 is at its maximum opening and the corresponding space opposite the face 19 at its minimum having ejected its contents.

As the rotor begins to rotate in the direction of the arrow in Figure 2 the rotor conforms to the shape of the curved wall 14 and the strip 21 is held against the face 17. The rotor thus rotates gradually to the opposite half of the chamber in the casing and the face 19 slowly retreats from the surface 17 exerting a suction on the port 25 which has been cleared by the strip 21. The rotor when turned half a revolution has brought the face 19 away from the surface 17 and the strip has shut off or nearly shut off the port 25. This movement is possible by reason of the end 24 of the shaft 13 being sealed in the slot 23. The slot allows the rotor to conform to the different angular positions on the shaft 13 which is fixed as to its axial position.

The axis of the shaft 13 is at an angle to the face 17. Assuming the rotor in position as in Figure 1 with the sealing strip 21 horizontal, one chamber only is open, that opposite the face 20 of the rotor. Now assuming a quarter turn of the shaft 13 and the rotor 18 the sealing strip, bearing always against the surface 17, is vertical. The faces 19 and 20 of the rotor are equidistant from the surface 17 and the two chambers are equal. As the rotor completes another quarter

turn, the sealing strip 21 is again horizontal and one chamber has become entirely open and the one previously open is now shut. The tilting or rolling that the rotor does while the strip 21 is passing from, say, horizontal to vertical position, or vice versa, is possible by reason of the connection with the shaft that permits such movement. The square end 24 and the slot 23 are found to serve satisfactorily as such a connection. In

10 comprehending the motions in this form of pump it must be observed that the strip 21 is at all times in contact with the face 17 of the plate 15 and can be of any desired size according to the duties for which the pump is designed. In the 15 absence of a sealing strip 21 the two faces 19 and 20 would come to a point in cross section which point would serve, of course, as the closure or separation between the two chambers formed opposite the faces 19 and 20.

20 A modified form of construction is shown in Figures 4 and 5. The face plate 15 is equipped with bearings 29. The bearings can be roller bearing or similar means in which a stud 30 rotates. The stud has an extension 31 projecting 25 through the face plate. The sealing strip 21 is fastened to this extension 31 and they turn together. In this form I show the faces 17, 19 and 20 slightly curved. The term straight is used to define the faces shown in Figures 1 and 6 although the faces might be made curved as shown 30 in Figures 4 and 5. The opposed faces, however, should be complementary in order to enable them to fit when the opposed faces are brought together.

35 In Figures 6, 7, 8 and 9, I show a further modification which contains a means for accurately regulating the time of opening and closing the ports and also embodying a rotatable disc as the abutment piece or end plate opposite the converging flat faces of the rotor. In this form the 40 rotor operates the same and rocks in its rotation due to the slot 23 receiving the square end 24 of the shaft 13. The sealing strip 34, however, is cylindrical in cross section and is secured to the reduced end 32 of the shaft which receives the 45 screw 33 which also passes into the sealing strip 34. Additional screws 35 on opposed sides of the shaft as shown in Figure 7 may be employed to secure the sealing strip to the rotor 18. The sealing strip is provided with a slot 36 to allow it to rock with the rotor 18 when the rotor rocks.

The rotor is opposite a disc 37 rotatable in the end plate 15 which is recessed to receive it. The face 38 of abutment disc 37 is in a plane passing 55 through the center of the sealing strip and the disc has a recess 39 to receive one half the sealing strip. The packing 40 can be installed to insure a tight joint and thus prevent leakage around the strip 34. The disc 37 can be supported as by the central pin 41 which rotates with the disc 37 and is covered by a cap 42. The plate 15 has an inlet port 43 and an outlet port 44. In the disc 37 are ports usually in the form of slots. These 60 slots are shown at 45 and 46 and it will be obvious that they can be proportioned to open or close the ports 43 and 44, with which they come in register, at predetermined times prior or subsequent to the complete closing of the chambers by the faces 19 and 20 of the rotor.

65 Various changes can be made in the form and proportion of the parts without departing from the scope of my invention.

I claim:—

1. A compressor comprising a casing having a chamber having a curved face on one side and a

straight face opposite the curved face, a rotor fitting the curved face and rotatable therein, said rotor having flat faces converging toward the centre of the straight face, said rotor also having a diametrically arranged central portion in 5 contact with the flat face of the chamber, and a shaft at an angle to the flat face of the chamber, the rotor and the shaft having co-acting means whereby the shaft and rotor can be rotated one from the other, the casing having inlet and outlet 10 ports.

2. A compressor comprising a casing having a chamber with a curved surface and a flat surface opposite the curved surface, a rotor in the chamber, said rotor fitting the curved surface and having 15 flat faces inclined relative to each other and having a diametrically arranged central portion to contact with the flat surface and means for rotating the rotor, the casing having inlet and outlet ports. 20

3. A compressor comprising a casing with a substantially semi-spherical chamber with a curved surface and a flat surface, a rotor fitting part of the curved surface and having inclined 25 faces, the planes of which converge the rotor having a centrally arranged sealing part bearing against the flat surface of the chamber, the casing having inlet and outlet ports.

4. A compressor comprising a casing having a chamber therein one inner face of which is substantially semi-spherical, a rotor with one face fitting said face of the chamber and having converging faces on the other side of said rotor, a shaft to rotate the rotor and having co-acting means to allow said rotor to gyrate to a limited extent, the chamber having an inclined wall at an angle to the axis of the shaft said latter wall having its surface complementary to the converging faces of the rotor as the rotor approaches the successive areas of the said wall surface in the 40 rotation of the rotor, the casing having inlet and outlet ports.

5. A compressor or the like comprising a casing with a substantially semi-spherical chamber having a flat wall opposite the curved wall, a rotor 45 fitting the curved wall of the chamber and having flat faces, each face in a plane radial relative to the center of the curved wall and converging toward said center, the rotor contacting with the flat wall of the chamber across the centre thereof, 50 and a shaft seated in the rotor and on an axial line bisecting the center of the flat wall of the casing and inclined relative to said flat wall, and an operative connection between the rotor and the shaft for driving the rotor and constructed 55 to allow the rotor to rock on said shaft as the rotor rotates with its centre contacting with the said flat face of the chamber the casing having inlet and outlet ports.

6. A compressor or the like comprising a casing 60 with a substantially semi-spherical chamber having a flat wall opposite the curved wall, a rotor fitting the curved wall of the chamber and having flat faces, each face in a plane radial relative to the center of the curved wall and converging 65 toward said center, the rotor contacting with the flat wall of the chamber across the centre thereof, and a shaft seated in the rotor and on an axial line bisecting the center of the flat wall of the 70 casing and inclined relative to said flat wall, a square part on the shaft, the rotor having a slot parallel with and in line with the convergence line of the walls of the rotor, said slot receiving the square part of the shaft and thereby allowing 75

the rotor to rock as it revolves with the shaft, the casing having inlet and outlet ports.

7. A pump comprising a casing having a semi-spherical chamber therein, said chamber having a flat face opposite the curved wall, a rotor in the chamber and having flat convergent faces and having a central contacting portion to form a closure across the diameter of the flat face of the semi-spherical chamber, and means for rotating the rotor causing the said contacting portion to sweep around in contact with said flat face, the casing having inlet and outlet ports.
- 5
8. A device of the kind described comprising a casing with a chamber therein, one wall of the chamber being flat and the opposite wall being semi-spherical, a rotor fitting part of the curved wall of the chamber and having converging flat faces, the portion of the rotor where the faces converge being constructed to form a diametrically disposed contact across the flat wall of the chamber and means for rotating the rotor on an axis inclined relative to the plane of the flat wall 10 of the chamber the casing having inlet and outlet ports.
